CENTRIFUGAL FLYING TOY**William O. Dodd, Jr., 2025 Lindell, and Clinton A. Hicks,
3906 N. Chadbourne, both of San Angelo, Tex.****Filed Feb. 5, 1958, Ser. No. 713,454****2 Claims. (Cl. 46—77)**

This invention relates to amusement devices and particularly to a toy that has a pilot stick together with a tethered object controlled by maneuvers of the pilot stick and line to which the object is secured.

An object of this invention is to provide an amusement device for all age groups, the amusement device having one or more of a large group of flying objects, for example rockets, airplanes, gliders, flying saucers, satellites, and many others too numerous to list, together with a flexible control line by which the flying object is tethered, and a pilot handle. These parts are connected in a manner which will enable the user to fly the tethered object in numerous patterns and perform numerous acrobatics, flight attitudes, etc.

An important feature of this invention involves the handle and its construction. The handle is made sectional so that it can be extended or shortened depending on the desires and needs of the user. Moreover, the longer handle will produce a different response than the shorter handle in the flight of the tethered object.

Another important feature of the invention is the control line inner end construction. A ring or other safety grip is at the extremity of the line and there is a full 360° fisherman's swivel connecting the ring to the line. This line can be constructed of fisherman's leader material, usually nylon, or some other stout and very light weight line material capable of withstanding considerable loads. By having the full 360° swivel, a large number of flight patterns can be achieved which would ordinarily be virtually impossible once the line became wound tight. The flight patterns in this category would include all of those that require the line to rotate.

It is clearly to be understood that various individuals using the amusement device will obtain considerable enjoyment by improvising various flights of the tethered object. Very few of the various flight patterns that can be accomplished with the amusement device are as follows: To complete a full horizontal circle and one or more half-circles, with the control line completely out as the object, for example an airplane, passes a person's back and approaches his right side, provided the handle is held in the right hand, grasp the retainer in the left hand and pull back to the left and in an outward direction with the retainer so that by the time the plane is in front, the right arm and handle have moved to the left together with the airplane and it will now circle in front of the person and by swinging the plane outwardly and away from the person while at the same time pulling back the control line, the full horizontal circle is resumed. To complete vertical circles, the retainer is taken by the left hand and moved outward and to the left in order that this taking up of flight line prevents the plane from crashing to the ground. While doing these vertical circles it is quite enjoyable to perform stalls. When the plane is above the user's head, the line is released and the airplane will plunge nose first downward to the ground in a full or partial stall. Before it crashes to the ground,

2

however, the slack in the line is pulled up and the airplane will climb out of the dive without crashing thereby performing a stall out.

5 A figure eight maneuver is accomplished while the plane is in vertical circle pattern. This is accomplished by transferring the vertical circles from a person's left hand to his right side and back again. The airplane and handle so complement each other that the airplane will maintain flight by merely pulling out and letting in on the retainer rhythmically rather than by wrist movement of the handle. Bringing the airplane in for a perfect three point landing may be obtained by skillfully utilizing the retainer and proper handle movements.

15 This invention, by virtue of the handle, retainer at the end of the control line, the control line itself and the tethered object achieves a feel at the retainer which actually transfers essentially the airplane and related control sensations.

20 Other objects, features of importance, operational flight patterns and uses will become apparent in following the description of the illustrated form of the invention.

Figure 1 is a schematic representation showing the invention in use.

25 Figure 2 is an elevational group view showing components of the sectional handle that constitutes a part of the invention.

Figure 3 is a fragmentary enlarged sectional view of the sectional handle and line.

30 Figure 4 is a perspective view of a suggested tethered object at the end of the line.

Figure 5 is a fragmentary front view showing the use of an auxiliary guide for the line near one wing tip of the airplane of Figure 4.

35 Figure 6 is a fragmentary perspective view showing connection of the line with the airplane without using the auxiliary guide.

In the accompanying drawings there is shown an amusement device 10 which exemplifies the principles of the invention. This amusement device has a tether object 12 at the outer end of a control line 14. The tether object is an airplane, although as previously indicated, the configuration may be altered throughout a very wide range of objects depending on manufacturing prerogatives, customer acceptance and other economic reasons.

40 The object 12 being an airplane, has a fuselage 16, wings 18, an empennage 20, a free turning propeller 22 and a landing gear 24. Counterweight 26 in front of the center of lift of the airplane is required in most instances.

45 Line 14 has a full 360° fisherman's swivel 28 near its outer end and a fastener 30 connecting the swivel to an eye 32 carried by the top of fuselage 16. Fastener 30 can also be a fisherman's fastener as is swivel 28. Moreover, the control line 14 should be flexible and strong,

50 especially to withstand impact shocks and therefore, nylon such as used in fishing leaders, is an excellent line material. Others such as different types of nylon, silk, cord, etc. can be used, although the nontwisted nylon such as found in fishing leaders, is excellent. Direct

55 connection (Figure 6) between the control line 14 and the fuselage is suggested for some maneuvers. Other maneuvers are better performed by using the auxiliary guide 34 near one of the wing tips. The auxiliary guide is made of a wire support 36 attached at one end of the wing and rising upwardly from the top surface of the wing. An eye 38 is formed at the upper extremity of the support, as by forming a ring of the wire. Control line 14 can be threaded into the eye or threaded therefrom (Figure 5). When the flying object 12 has some

60 other configuration, there will be in common, an eye 32 or corresponding means by which to attach the outer end

65 70 75 80 85 90 95

of the control line 14 to the object. The auxiliary guide 34 can be used or omitted.

The inner end of line 14 has a fisherman's swivel 48 capable of a full 360° rotation, attached to it and a fastener 50 secured to the swivel 48. Finger ring 52 is secured to fastener 50 so that the ring can be held fixed while line 14 is capable of rotating. Finger ring 52 can be substituted by a knob or any other easily held article.

Handle 54 has the control line 14 passed through its longitudinal passageway 56. The passageway extends completely through the handle that is formed of a plurality of sections. Four typical sections 58, 60, 62 and 64 are shown in Figure 2. The lowermost section 58 has a hand grip 66 that can be made in several ways, one of which is to have upper and lower ribs 68 and 70 between which there are peripheral grooves 72. It is preferred, although not essential, that the handle sections be made of plastic. The handle section 58 has a bore 74 that constitutes a part of passageway 56, and the lower end of the bore has a smaller diameter, smooth-edged opening 76. The edges of opening 76 guide the line 14 as it moves in and through passageway 56.

Section 60 and section 62 are identical. The section 60 has a bore 78 and a counterbore 80, each of which constitutes a part of the passageway 56. Shoulder 82 separates the reduced diameter portion 84 within which the bore 78 is formed, and the shoulder abuts the outer end of section 58 when the reduced portion 84 of section 60 is inserted in bore 74. The same construction and method of attachment applies to the connection between section 62 and section 60. Section 64 is tubular, having a central bore 86. It fits in the bore of section 62 and is held in place by friction. The sections can be cemented together or merely held together by friction, this depending on the desire of the owner. Just as the edges of opening 76 are smooth, the edges of opening 88 at the outer end of section 64 must be smooth to prevent abrasion of control line 14.

It is understood that various modifications and changes may be made without departing from the invention as claimed.

What is claimed as new is as follows:

1. An amusement device comprising a tethered object, a flexible control line, a swivel connector attaching said object to the outer end of said control line, a ring adapted to be held by one hand of a user of the device, a swivel directly connected to said ring and to the inner end of

said control line thereby isolating the part of said control line between said tethered object and said ring from the hand of the user and from said tethered object whereby to enable turning of said control line about its longitudinal axis independently of said ring and object, a straight control handle adapted to be held in the other hand of the user and having a straight, uninterrupted longitudinal passageway extending therethrough in a straight line from end to end thereof, said control line extending in a straight line through said passageway and being freely slidably disposed and rotatable therein, said handle consisting of a plurality of straight sections each having an end to end bore therethrough constituting part of said passageway, adjacent ends of parts of adjacent sections having a telescoping engagement with each other and with the end of one section of a pair being of reduced external and internal diameter and being telescopingly received in the adjacent end of the other section of said pair, said sections being separably connected by said telescoping engagements whereby to alter the length of said handle while maintaining said continuous passageway therethrough by varying the number of connected sections, said control ring and the rotatable and slidably disposition of said isolated part of said control line in said handle enabling control force to be applied to the control line at one end thereof by one hand of the user while the handle is independently manipulated by the other hand of the user whereby to effect sensitive control of said tethered object.

2. The combination of claim 1 wherein said reduced end portions of said handle sections have diametrically reduced bores extending therethrough whereby to reduce the clearance of the control line in its movement within said passageway.
